UNITED STATES PATENT OFFICE.

ALBERT S. WEAKLEY, OF GRETNNA, FLORIDA.

WIND-SHIELD.

1,315,691.

Specification of Letters Patent. Patented Sept. 9, 1919.

Application filed March 12, 1918. Serial No. 221,975.

To all whom it may concern:

Be it known that I, ALBERT S. WEAKLEY, a citizen of the United States, and a resident of Gretna, in the county of Gadsden 5 and State of Florida, have invented certain new and useful Improvements in Wind-Shields, of which the following is a specification.

My present invention relates to wind-shields, and more particularly to a structure adapted for use in conjunction with windshields as now used upon automobiles 10 and other vehicles.

The principal object of my invention is 15 to provide a structure of the character set forth which can be made up as an attachment to be fitted in conjunction with windshields now already in use, or which can be embodied with windshields as manufactured, 20 and which will give a clear vision in stormy weather.

A further object is to so construct the device that the entire upper portion of a windscreen to which the device is fitted is 25 protected from rain, snow, and the like, even where the same is driven by the wind and when the vehicle is in motion.

Yet another object is to arrange means 30 by which adjustment of the parts can be made to suit varying conditions of use, and to provide a structure by which such adjustment is permitted and is compensated for.

Further objects of my invention will appear 35 in the following detailed description, taken in connection with the accompanying drawing, forming a part of this specification, and in which drawing:

Figure 1 is a perspective view showing 40 the device of my invention as it would be fitted for use.

Fig. 2 is a transverse vertical sectional view taken through the structure shown in Fig. 1.

Fig. 3 is a detail view showing a hinged bracket by which the main support of the device is accomplished when the structure is fitted as an attachment.

Fig. 4 is a view somewhat similar to 50 Fig. 3 showing a supplemental attaching bracket.

In the drawing, where similar characters refer to similar parts throughout the views, A designates, generally, a windscreen structure as now already commonly used, only 55

the upper portion being shown. This wind-shield structure may be of the form here illustrated or of any other desired or standard construction, and as it is the purpose of this invention to provide parts by which the upper portion of the standard wind-shield will be protected, the hood portion B is fitted by brackets C to be disposed on the forward side of the upper part of the wind-shield structure, this hood portion being 60 hingedly mounted through the brackets C, and thus capable of adjustment to various angular settings. Adjusting means by which the shield is moved to different positions, and by which it is held in set relations, is generally indicated at D, and to guard against rain or snow driving in at the ends of the hood member B, the end portions E are provided, these being arranged to allow for different angular settings of the 65 hood portion B.

While I have here illustrated the wind-shield portion A very diagrammatically and as being made up of a frame having a glass carried thereby, it will be understood that 80 the device of the character mentioned might just as well be fitted in conjunction with supporting uprights by which a swinging windscreen member is carried, and as the description progresses, it will be appreciated that the operation of the parts and the utility of the structure would be the same in other adaptations. The bracket portions C are made up of the members 5 and 6, which are hingedly or pivotally connected together by the bolts 7, and the hood portion B, which consists of a frame 8 having a glass 9 carried thereby has the members 6 connected therewith so a firm connection and pivotal mounting is accomplished 90 for the hood. As is here shown, the member 5 has a clamp plate 10 formed as a part thereof and a clamp plate 11 is provided to coöperate with the plate 10 and to be held by a bolt 12, so that the two plates will embrace and catch upon the frame structure of the windscreen A, the parts being thus detachably fitted and adapted for use upon various types of windshields. It is preferable that the frame portion 8 be made of 100 substantially U-shaped form as shown in Fig. 1, and that any frame structure at the lower edge of the glass 9 be avoided as in this construction no opaque material is introduced to obstruct the vision through the 110

glass of the windshield A. As has been stated, it is the intention that the hood portion B shall protect the glass of the windshield A from driving rain, snow, and the like, and therefore the curved shield plate 13 is provided on the upper cross bar of the frame 8, this shield plate being curved in an arc around the pivot bolt 7 so that as the hood is fitted in place by securement of the bracket portions C, the shield plate will extend over the upper edge of the windshield A and irrespective of the adjustment of the hood portion B will close the space between the hood and the windshield and will thus positively preclude the possibility of rain driving through at this point.

It is intended that the hood structure B shall be set to extend with the glass 9 substantially parallel with the glass of the windshield A, or shall be raised to extend substantially at right angles thereto, and to secure these adjustments and hold the parts in the adjusted relations, the rod D is employed. As shown in Fig. 4, a bracket portion consisting of the plates 14 and 15 is provided to be set and held upon the windshield frame by the bolt 16, and this bracket portion has a bearing extension 17 provided on one of the plates thereof. The bearing extension 17 has an opening through which the rod D is received slidably, and as this rod D is secured in conjunction with the frame 8 and is arched or curved throughout its extent with the pivot bolts 7 as the center of the arc, the occupant of the vehicle can readily adjust the hood B by grasping the knob or handle 18 and either shoving or drawing the rod through the opening in the bearing extension 17. The rod D preferably has a sufficiently tight frictional set through the opening of the bearing extension that adjustment will be held, but it will of course be appreciated that some positive locking means, such as is now employed in other like connections, might be introduced to perform this function.

The end members E are of fabric, leather, or other suitable material, and are laid in accordion or bellows folds, so that as the hood portion B is adjusted they will expand or take up to neatly and securely close the ends of the space between the two frame portions. It will of course be understood that the end members E will be preferably secured throughout the entire extent of the end of the frame portion 8, and attachment upon the windshield proper might be made at the bracket plates in conjunction with which the rods D are mounted, or special fastenings might be employed in this connection. Rings 19 are carried by the end portions E at the lower edge thereof and are fitted loosely around the rods D so that as the end portions are folded the material

thereof will be held against sagging out or bulging as might otherwise occur. It will of course be understood that adjusting rods D will be provided at each side, and thus by grasping either of the knobs 18, or both at the same time, the hood portion can be adjusted.

The manner of applying the device of my invention, and the function accomplished in use, has been rather fully set forth as the description has progressed, and it is therefore not deemed necessary to here indulge in recapitulation.

Other changes in details of construction and in the manner of applying the device for use, than those herein specifically mentioned, may be made without departing from the spirit or scope of my invention; but,

I claim:

1. An attachment for windshields including with a frame having a glass carried thereby, bracket members by which said frame is detachably fitted in swinging mounting adjacent the top of a windshield, a shield plate carried by the frame to close the space between the said frame and the windshield, brackets to be detachably mounted on the windshield structure below the points of mounting of the pivoting brackets and each provided with bearing extension, curved rods mounted in conjunction with the frame slidably received through the openings of the bearing extensions, and end portions of expandable material closing the space between the frame and said windshield and adapted to take up and expand as said frame is adjusted. 85 90 95 100

2. An attachment for windshields including with a frame having a glass carried thereby, bracket members by which said frame is detachably fitted in swinging mounting adjacent the top of a windshield, a shield plate carried by the frame to close the space between the said frame and the windshield, brackets to be detachably mounted on the windshield structure below the points of mounting of the pivoting brackets and each provided with bearing extension, curved rods mounted in conjunction with the frame slidably received through the openings of the bearing extensions, portions of expandable material closing the space between the frame and said windshield and adapted to take up and expand as said frame is adjusted, and rings mounted in conjunction with the end portions fitted slidably upon said rods to hold the end portions and maintain the same in proper relation. 105 110 115 120

3. The combination with a windshield, of a hood structure including a frame, a glass pane carried by the frame, means pivotally connecting the frame at its top edge to the top of said windshield, a shield plate formed upon the upper edge of said frame and curved in an arc about the pivot of the frame 125 130

for extending over the upper edge of the windshield under all adjusted positions of the frame, curved rods carried by the hood frame, means carried by the windshield and 5 slidably receiving said curved rods, portions of expandible material closing the space between the hood frame and said windshield and adapted to take up and expand as the frame is adjusted, and rings carried by said expandible material and slidably mounted 10 upon said curved rods to hold the expandible end portions and maintain them in proper relation.

ALBERT S. WEAKLEY.
